UNITED STATES PATENT OFFICE.

WESLEY L. WISEMAN, OF CANTON, OHIO.

MATCH-BOX.

1,199,954.

Specification of Letters Patent

Patented Oct. 3, 1916.

Application filed June 5, 1915. Serial No. 32,368.

To all whom it may concern:

Be it known that I, WESLEY L. WISEMAN, a citizen of the United States, residing at Canton, in the county of Stark and State of Ohio, have invented a new and useful Match-Box, of which the following is a specification.

My invention relates to improvement in match boxes which consists in providing a box preferably made of paste-board and so constructed that it can be used in trade as an ordinary and common match box.

The objects of the present invention are, first, to provide a match box of simple construction and one that can be suspended from a nail in the wall and a quantity of the matches exposed for use from time to time, and second, to provide means for moving a portion of the match holding receptacle in a position to expose the matches. These objects, together with other objects readily apparent to those skilled in the art, may be attained by the construction illustrated in the accompanying drawings, although the invention may be embodied in other forms, the construction illustrated being chosen by way of example.

In the accompanying drawings: Figure 1 is a perspective view of the box in closed position. Fig. 2 is a perspective view of a match box embodying the invention, showing the same when in position for use as a magazine. Fig. 3 is a perspective view of the inner box and its different parts. Fig. 4 is a back view of the box showing the same in the position illustrated in Fig. 2. Fig. 5 is a transverse section on line 5—5, Fig. 4. Fig. 6 is a view of the paste-board from which the inner box is made, except the part to be attached thereto.

Similar numerals of reference indicate corresponding parts throughout the several figures of the drawings.

In the accompanying drawing, 1 represents the outer box which is rectangular in form and of the usual size. Within the box 1 is normally located the match containing box 2 which is formed of a size to fit the outer box 1. One end of the match holding box 2 and what might be termed the lower end, reference being had to the position shown in Fig. 2 is provided with the tray 3, which tray is closed at its ends by the end pieces or flaps 4.

To the tray end of the box 2 is attached by

means of glue or otherwise the strip 5 which strip is extended upon either side of the box 2, thereby constituting the flaps 6. When it is desired to place the box 2 in the box or cover 1, the tray, its different parts and the flaps 6 are folded or closed and all inserted in the box or cover 1. It will be understood that the ends 4 of the tray 3 will lie between the sides of the box 2 and the flaps 6. It will also be understood that before the matches can be located in the tray 3 the box 2 must be slid down or endwise with reference to the cover 1 at which time the tray can be brought into the position shown in Fig. 2.

For the purpose of convenience in bringing the tray into proper position, its outer edge is provided with the pull-lip 7. For the purpose of holding the box 2 in proper relative position with reference to the cover 1 the upper end of the box 2 is provided with what might be termed a common paper fastener, which consists of the split shank 8 and the head 9. The cover 2 is provided with the aperture 10 which is formed of a size to permit the head 9 to be passed therethrough, said cover is also provided with the elongated slot 11, which permits the inner box to be moved or slid endwise with reference to the box or cover 1, the sliding movement corresponding to the length of the slot 11, the further movement of the box 2 is limited by reason of the paper fastener striking the bottom of the slot 11.

It will be understood that when the inner and outer boxes are brought into the position shown in Fig. 2 that the aperture 10 will be open and the box can be suspended by a nail or its equivalent. For the purpose of preventing the paste-board from being torn by reason of the box being suspended upon a nail the back of the cover 2 should be provided with the reinforcing strip 12, which reinforcing strip may be attached in any convenient and well known manner.

It will be understood that the outward movement of the tray will be limited, owing to the fact that the top or upper portions of the ends 4 will strike against the inner surface of the box or cover 1 when the box proper is in the position shown in Fig. 2.

Having fully described my invention what I claim as new and desire to secure by Letters Patent, is:

In a magazine match box comprising an

outer box and an inner box, slidably connected together, said inner box provided with a foldable tray, said tray provided with end members and a pull-lip located intermediate the end members of the tray, a strip secured to the inner box and provided with wings, said wings adapted to embrace the end mem-

bers of the tray, and means for limiting the sliding movement of the inner and outer boxes with reference to each other. 10

In testimony that I claim the above, I have hereunto subscribed my name.

WESLEY L. WISEMAN.
